CONTAINER

Sol Stone, Brooklyn, N. Y.

Application September 26, 1938, Serial No. 231,706

1 Claim. (Cl. 312—190)

This invention relates to containers and while not limited thereto, the same has particular reference to a container which serves as a wardrobe for the storage of clothing to protect the same against attacks of moths and other insects.

The invention primarily comprehends a container having guide means at opposite edges of the mouth opening and a closure panel slidably engaging the guide means and which is collapsible from an extended condition to a compactly folded condition when moved from closed to opened relation and expandable from a compactly folded condition to an extended condition when moved from opened to closed relation.

The invention further embodies a container having guide channels at opposite edges of the mouth opening with parallel guide elements extending longitudinally of the guide channels and a plaited closure panel slideable on the guide elements and in the guide channels for collapsing the same from extended condition to a compactly folded condition when the closure is moved from closed relation to opened relation and for expanding the closure from a collapsed folded condition to extended condition when the closure is moved from opened to closed relation.

The invention further comprehends, in a container of the indicated character, a plaited closure panel which is collapsible in the plane of the mouth opening from extended closed relation to a compactly folded opened relation so as to occupy a minimum amount of space adjacent one end of the mouth opening and which when opened does not interfere with the contents of the container while affording a mouth opening of maximum size for admitting to or removing articles therefrom.

With the foregoing and other objects in view, reference is now made to the following specification and the accompanying drawing in which there is illustrated the preferred embodiment thereof.

In the drawing:

Fig. 1 is a perspective view of a container constructed in accordance with the invention with parts broken away to disclose the underlying structure and with the closure in partially opened condition.

Fig. 2 is an enlarged fragmentary vertical sectional view taken approximately on the line 2—2 of Fig. 1.

Fig. 3 is an enlarged horizontal sectional view taken approximately on the line 3—3 of Fig. 1.

Referring to the drawing by characters of reference, the container includes a body section com-

prising integral, foldably connected rear and side walls 10 and 11, and oppositely disposed front wall portions 12 connected to the forward vertical edges of the side walls 11.

The body section also includes a rectangular closure frame preferably constructed of wood and which is composed of vertical side stiles 13 and transversely extending end strips 14 secured to the side stiles at the opposite ends thereof. The side stiles 13 are formed with longitudinally extending guide channels 15 opening through the confronting edges thereof and longitudinally extending grooves 16 opening through the outer longitudinal edges thereof in which grooves are received the inner longitudinal edges of the front wall portions 12.

The closure frame further includes parallel guide elements such as rods 17 which extend longitudinally of and are disposed substantially centrally within the guide channels 15 and have their opposite ends anchored in transverse cleats 18 and 19 secured at their ends to the side stiles 13 and which cleats are located and secured in contact with the rear surface of the end strips 14 adjacent the bottom edges thereof.

The body section also includes a closure constructed of a flexible material such as paper-board, fabric and the like and which consists of a transversely plaited accordion foldable panel 20 anchored along its bottom edge to the transverse cleat 19 and secured along its upper transverse edge to a cross bar 21. The cross bar 21 and the plait of the panel 20 are provided with registering apertures 22 adjacent their opposite ends through which apertures the rods 17 extend for sliding movement of the panel 20 and bar 21 thereon. The cross bar 21 at the opposite ends thereof and the closure panel 20 at the opposite side edges thereof are disposed within the guide channels 15 to enclose the same and seal the vertical edges of the mouth opening when the closure panel is disposed in closed relation. The guide channels 15 also serve as guide means for the cross bar 21 and prevent inward and outward buckling of the closure panel 20 when closed or being moved to or from closed relation.

The closure panel 20 is slideable downwardly on the rods 17 from an extended condition to a compactly folded condition when moved from closed to opened relation and when in compactly folded condition is located at the rear of the bottom end strip 14. When the closure is to be moved from folded condition to an extended condition, the same is slideable upwardly on the rods 17 and releasably secured in closed relation by interen-

gageable latch and keeper means 23 and 24 carried respectively by the cross bar 21 and the upper end strip 14.

The container also includes top and bottom sections comprising end panels 26 having inwardly directed reinforced flanged edges 27 which telescopically fit over the opposite ends of the body section with the forward flanged edge engaging over the end strips 14 and with the inner edges thereof abutting against the end edges of the side stiles 13.

What is claimed is:

In a wardrobe container having a walled hollow body structure with an opening through one wall for introduction and removal of articles of clothing, a unitary rectangular closure frame surrounding said opening provided with vertical side stiles and transversely extending top and bottom stiles, said side stiles being provided with longitudinally extending guide channels in the confronting faces thereof, guide rods disposed substantially centrally within the guide channels and consequently located laterally outwardly from the access opening into the container, a transversely pleated longitudinally extensible closure panel connected at its lower end within the closure

frame and behind the transversely extending bottom stile, a rigid cross bar secured to the upper end of the pleated closure panel and movable therewith, the pleated edges of said panel and the ends of said cross bar being received at each side within the longitudinally extending guide channels of the vertical side stiles and being provided with registering openings adjacent to their opposite ends through which the guide rods are received, said cross bar and the pleated closure panel being slideable on said guide rods and within the guide channels whereby the cross bar normally exerts weight to collapse to pleated extensible closure panel in the lower part of the container opening and behind the transverse bottom stile and the guide rods being entirely within the guide channel whereby when the closure panel is opened the opening through the rectangular frame into the container is entirely free and unobstructed and the pleated closure is protected by the bottom stile and the cross bar while the guide rods are protected by the vertical side stiles of the frame, and releasable means engageable with said cross bar to hold the pleated panel in raised and closed position.
